INVERTIBLE ROTATABLE DISPLAY STAND

Allan M. Patrick, 5990 Veronique St.,
Ville Brossard, Quebec, Canada

Filed Oct. 2, 1969, Ser. No. 19,376

Term of patent 14 years

Int. Cl. D6—01

U.S. Cl. D80—9

FIG. 1 is a side elevational view of an invertible rotatable display stand showing my design.

FIG. 2 is a top plan view.

FIG. 3 is a rear elevational view thereof in the inverted position.

FIG. 4 is a bottom plan view thereof.

FIG. 5 is a side view of FIG. 1 taken ninety (90) degrees to the left; and

FIG. 6 is a side view of FIG. 1 taken ninety (90) degrees to the right.

I claim:

The ornamental design for an invertible rotatable display stand, as shown.
